UNITED STATES PATENT OFFICE

2,420,479

CURTAIN

Nell S. Hicks, Atlanta, Ga.

Application September 20, 1944, Serial No. 554,950

2 Claims. (Cl. 160—349)

1

The invention relates to a window curtain, and more especially to a combined curtain and tie-back therefor.

The primary object of the invention is the provision of a structure of this character, wherein curtains can be properly hung and draped, to give pleasing appearance thereto when supported at a window or the like, and without such curtains becoming disarranged from their normal draped condition, thereby affording attractiveness to the same from one season of the year to another, and pleasing effects to an observer.

Another object of the invention is the provision of a structure of this character, wherein the same can be conveniently hung with dispatch and ease, and pleasingly draped from a window or the like, for giving a tidy appearance thereto.

A further object of the invention is the provision of a structure of this character, which is simple in its make-up, thoroughly reliable and efficient for the purposes intended thereof, neat and attractive in appearance when hung, and inexpensive to manufacture and install.

With these and other objects in view, the invention consists in the features of construction, combination and arrangement of parts as will be hereinafter more fully described, illustrated in the accompanying drawings, which show the preferred embodiment of the invention, and pointed out in the claims hereunto appended.

In the accompanying drawings—

Figure 1 is an elevation of the curtains with the tie-back constructed in accordance with the invention.

Figure 2 is a front view of the curtains prior to the draping and tieing back of the same to a window or the like.

Figure 3 is an edge view thereof.

Figure 4 is a plan view of the tie-back.

Figure 5 is a plan view of the pattern of one of the curtain sections.

Similar reference characters indicate corresponding parts throughout the several views in the drawings.

Referring to the drawings in detail, A designates generally the structure constituting the present invention in its entirety, and comprises a pair of curtain sections 10 made from any suitable fabric material, each normally of the pattern, best shown in Figure 5, having a normally straight bottom edge 11, a diagonal top edge 12, and straight opposite side edges 13, respectively. These sections 10 in the mounting thereof at a

2

window or the like B are arranged in biased overlapped relationship, as best seen in Figures 1 and 2 of the drawings, they having the ruffled edging 14 or not, and such sections are suspended at their top portions by any suitable suspension means not shown, to the framing of the window or the like B.

At an appropriate intermediate area of each section, on the innermost side thereof is formed a 10 diagonally disposed casing 15, crosswise thereof. Each casing 15 is designed to removably and adjustably receive a tape, cord or the like 16 of a tie-back 17, the latter being equipped with an eye or ring 18, while the outer end of the tape, cord or the like 16, is likewise equipped with an eye, ring or the like 19, both 18 and 19, are adapted for detachable engagement with a fastener 20 on each side upright of the frame of the window, or the like B, as best seen in Figure 1 of the drawing, so that the sections will hang draped, with the tie-backs 17 outwardly of such sections.

What is claimed is:

1. A structure of the kind described, comprising a curtain section having a casing built therewith intermediate the ends thereof, a tie-back having a ruffled portion an eye at one end of said ruffled portion for detachable fastening to a support, and an extension at the other end of the ruffled portion of the tie-back and removably trained through the casing, and having an eye at its outer end for engaging said support.

2. A structure of the kind described, comprising a curtain section having a casing built therewith intermediate the ends thereof, a tie-back having a ruffled portion an eye at one end of said ruffled portion for detachable fastening to a support, and an extension at the other end of the ruffled portion of the tie-back and removably trained through the casing, having an eye at its outer end for engaging said support, and a diagonal edge formed at the top portion of the section, and the remaining side and bottom edges thereof being normally straight.

NELL S. HICKS.
